UNITED STATES PATENT OFFICE.

HUGH R. WILLIAMS, OF CHICAGO, ILLINOIS.

KNOB-ATTACHING MEANS.

1,313,147.

Specification of Letters Patent.

Patented Aug. 12, 1919.

Application filed February 19, 1917. Serial No. 149,489.

To all whom it may concern:

Be it known that I, HUGH R. WILLIAMS, a citizen of the United States, residing at Chicago, in the county of Cook and State of Illinois, have invented a certain new and useful Improvement in Knob-Attaching Means, of which the following is a full, clear, concise, and exact description, reference being had to the accompanying drawings, forming a part of this specification.

This invention relates to improvements in door knob attaching means and has for its object to provide improved knob attaching means of simple construction that will afford a secure and quick adjustable connection between the knob and shaft.

The invention comprehends attaching means including a ratchet on one of the parts and a cooperating dog on the other part with actuating and retaining means for the dog. An important novel characteristic feature of the invention resides in the special construction and arrangement of the dog and retaining means, whereby the parts can be quickly assembled in operative position, and the dog readily removed to permit the knob to be disconnected from the knob shaft.

I will explain one form which my invention may take more in detail by referring to the accompanying drawing, in which—

Figure 1 is an end view of a door, portions of the knob structure being broken away more clearly to reveal features of construction;

Fig. 2 is a sectional view on line 2—2 of Fig. 1, and

Fig. 3 is a perspective view of one of the automatic locking elements.

I show in Fig. 1 a portion of a door 10 provided with the lock 11, said lock having the customary latch 12 and bolt 13. This lock is fastened in the door and has the square shaft or stem 14 projecting therethrough, said stem controlling the actuations of the latch 12. This stem is provided with a pair of knobs 15, 15, which knobs are held in position upon this stem through the agency of the improved construction which forms the subject matter of my invention.

In accordance with my invention I provide teeth or other serrations 16 along the upper edge of the stem. The shank of the knob is then provided with a slotted portion 55 which carries a locking element 17, this lock-

ing element being adapted to enter the serrations and to hold the knob 15 in position upon the stem. In order yieldingly to press this locking element 17 into the serrations, I provide a split ring 18 made of springy material, which ring encircles the shank of the knob and presses the locking element 17 inwardly. Thus in order to mount the knob 15 upon the stem 14, all that is necessary is merely to insert the stem into the opening 19 provided therefor in the knob. The locking element 17 then falls into the serrations and prevents a return movement of the knob after it is mounted in position. Suitable rings or distance pieces 20 may control the position of the knob relative to the door. The door plate 21 has a central opening 22 so that the spring-like ring 18 may be moved out of register with the locking element 17 should it be desired at any time to remove the knob from the stem 14. However, the arrangement may be such that an unusual application of force to the knob may permit its withdrawal, this merely depending, of course, upon the nature of the serrations 16.

From what has been thus described the nature of my invention will be readily clear to those skilled in the art.

Having however thus described one form of my invention may take, what I claim as new and desire to secure by Letters Patent is:

A device for adjustably connecting a door knob with a latch controlling spindle, comprising a latch controlling spindle having one end portion thereof provided with a series of teeth extending transversely of the spindle, a door knob having a hollow annular extension adapted to fit over the toothed end portion of the spindle, the annular extension having a transverse slot intermediate the ends thereof, a locking dog consisting of a flat arcuate plate, the straight edge of the plate being adapted to engage the transverse teeth of the annular extension, said locking plate being slidable laterally through the slot in said annular extension into engagement with the toothed end portion of the spindle, and a split annular spring locking ring encircling the annular extension and adapted to engage the outer curved edge face of the locking plate to hold the same in engagement with the toothed end portion of the spindle, the locking ring being adapted to 110

yield as the knob and dog are slid inwardly on the toothed end portion, and said locking ring being slidable longitudinally of the annular extension to one side of the trans-
5 verse slot therein to permit of the insertion into and withdrawal therefrom of said dog.

In witness whereof I hereunto subscribe

my name this 16th day of February, A. D. 1917.

HUGH R. WILLIAMS.
